Des. 229,881
Patented Jan. 15, 1974

229,881

BUTTER DISH

Leon Camp Gillespie, 2714 Montana St.,
El Paso, Tex. 79903

Filed Feb. 11, 1972, Ser. No. 225,690

Term of patent 14 years

Int. Cl. D7—01
U.S. Cl. D7—84

FIG. 1 is a front elevational view of a butter dish showing my new design, the rear view being identical thereto;

FIG. 2 is a side elevational view thereof;

FIG. 3 is a top plan view thereof; and

FIG. 4 is an exploded view thereof in cross-section.

I claim:

The ornamental design for a butter dish, as shown and described.
